GRAB RAIL AND SEAT ATTACHMENT FOR
BATHTUBS

George B. Bentz, New York, N. Y.

Application February 28, 1938, Serial No. 193,199

5 Claims. (Cl. 155—36.5)

The invention aims to provide a novel bathtub attachment embodying both a seat to overlie the tub side wall, and a grab rail to assist when entering and leaving the tub.

5 In carrying out the above end, a further object is to provide a simple and inexpensive, yet an efficient and reliable clamping means for effectively clamping the attachment to the tub side wall.

10 Another object is to provide unique means for rotatably mounting the seat if desired.

With the foregoing in view, the invention resides in the novel subject matter hereinafter described and claimed, description being accomplished by reference to the accompanying drawings.

Fig. 1 is a perspective view showing one form of the invention upon the side wall of a bathtub.

20 Fig. 2 is a transverse sectional view through the tub wall and one of the vertically adjustable clamp members, the rest of the invention being shown in elevation.

Fig. 3 is a detail sectional view on line 3—3 of Fig. 2.

25 Fig. 4 is a perspective view of one of the vertically adjustable clamp members and the bolt and wing nut associated therewith.

Fig. 5 is a perspective view of the construction above described, looking upwardly.

30 Fig. 6 is a side elevation showing a different form of construction in place upon the side wall of a rolled rim tub.

Fig. 7 is a perspective view of the construction shown in Fig. 6.

35 Fig. 8 is a view similar to Fig. 6 but showing a still further construction.

Fig. 9 is a perspective view of the construction shown in Fig. 8.

40 Figs. 10 and 11 are views similar to Figs. 8 and 9 but showing a still further form of construction.

Fig. 12 is a sectional view showing a rotatable seat which may be used if desired, in connection with any form of the invention above described.

45 Fig. 13 is a disassembled perspective view showing the preferred manner of rotatably mounting the seat.

In Figs. 1 to 4, two arched clamps 12 are provided disposed in spaced parallel planes and rigidly connected by a grab rail 13. The upper portions of the clamps 13 support a seat 14 which may either be of fixed or non-rotatable type.

50 Each clamp 12 comprises a crown portion 15 to extend over the tub side wall, an inner vertically elongated leg 16 rigidly joined to one end of the crown portion 15, and an outer vertically elongated leg 17 rigidly joined to the other end of said crown portion, said legs 16 and 17 being preferably integral with said crown portion 15. The grab rail 13 is rigidly connected at its ends with the lower ends of the inner legs 16 of the two clamps 12, said ends of said grab rail being preferably extended laterally in the same direction as shown at 18 and integrally joined to said legs 16. The crown portions 15 of the two clamps 12 are preferably provided with rubber buttons or 10, the like 19 to rest on the tub rim, and the outer legs 17 are preferably provided with similar buttons 20 to abut the outer side of the usual double-walled tub. The legs 16 of the clamp members 12, however, are provided with adjustable clamp members 21, and a description of one of these clamp members will suffice for both.

The clamp member 21 comprises a vertical plate 22 disposed at the side of the leg 16 toward the tub side wall, and parallel vertical flanges 23 integral with or otherwise joined to said plate 22 and slidably straddling said leg 16, said flanges 23 being provided with elongated slots 24 which diverge upwardly with respect to said leg 16. In the present disclosure, a clamping bolt 25 passes through the leg 16 and through the slots 24 and the portions of said bolt which project beyond said leg, cooperate with the slot walls to wedge the clamp member 21 to clamping position when said clamp member is lowered 30 with respect to said leg. Preferably a wing nut 26 is provided on one end of the bolt 25 and the bolt head is provided with diametrical ribs or the like 28 receivable in one of the slots 24 to hold said bolt against rotation when turning said nut. 35 By loosening the nut 26 and downwardly forcing the clamp member 21, the clamp 12 may be tightly engaged with the tub side wall. Then by tightening the nut 26, the flanges 23 are inwardly moved into tight frictional engagement with the leg 16 40 to hold said clamp member in operative position. If desired, a screw 29 may be carried by the clamp member 21 to abut the lower end of the leg 16 for forcibly sliding said member 21 downwardly. In the present showing, the screw 29 is threaded 45 upwardly through a bottom flange 30 which extends between the lower ends of the side flanges 23. Preferably, the plate 22 is provided with a covering 31 of rubber or the like to prevent injury of the tub wall.

To facilitate lifting and release of the clamp member 21 when the attachment is to be removed from the tub, I have shown a handle 32 on one of the flanges 23 but the use of such a handle is, of course, optional.

In Figs. 6 and 7, two clamps 12^a support a stationary or rotatable seat 14^a and the inner legs 16^a of these clamps are integrally connected by means of a grab rail 13^a. The outer legs 17^a of the clamps 12^a are each provided with an integral horizontal extension 33 to underlie the rolled rim 34 of an older type of bathtub, said extension 33 having an upstanding lug or the like 35 which assists in providing a seat 36 for the lower edge of said rim. A horizontally swingable arm 37 is connected with the extension 33 by a clamp bolt or the like 38, said arm 37 being provided with a clamp member 39 to abut the outer side of the tub wall. An adjustable clamp member 21^a which may be considered as identical with the member 21, is carried by the leg 16^a to abut the inner side of the tub wall.

In Figs. 8 and 9, the two clamp members 12^b which support the seat 14^b, include inner legs 16^b integrally connected by the grab rail 13^b, and outer legs 17^b for disposition at the outer side of the rolled rim 34^b. Horizontally swingable arms 37^b are provided to extend under the rim 34^b, said arms being provided with bearings 38^b rotatable upon the lower ends of the legs 17^b. These arms are provided with clamp members 39^b to abut the outer side of the tub wall, and the legs 16^b are provided with adjustable clamp members 21^b to abut the inner side of said wall, said clamp members 21^b being preferably identical with the clamp members 21 and 21^a.

In Figs. 10 and 11, the clamps 12^c which support the seat 14^c are provided with inner legs 16^c integral with their crown portions 15^c, and with outer legs 17^c also integral with said crown portions 15^c, and the laterally turned ends 18^c of the grab rail 13^c are integral with the lower ends of said legs 16^c. The crown portions 15^c are provided with rubber buttons or the like 19^c to rest on the tub side wall, the other legs 17^c are provided with similar buttons or the like 20^c, and adjustable screws 21^c are threaded through the legs 16^c to abut the inner side of the tub wall.

When the seat 14, 14^a, 14^b or 14^c is to be of fixed nature, it may be secured upon the crown portions of the clamps in any suitable way, for instance, by ordinary screws, bolts or the like, or by short straps such as those shown at 40 in Figs. 10 and 11.

When the seat is to be of rotatable type, a lower plate 41 (see Figs. 12 and 13) is secured in any suitable way upon the crown portions of the two clamps and the seat is formed by another plate, the two plates being connected by a central pivot 42. A spider 43 is interposed between the two plates, is rotatable on the pivot 42, and is provided with rings 44 which receive bearing balls 45, said balls contacting with the two plates and thus anti-frictionally supporting the seat for rotation, to aid in entering and leaving the tub. Handles 46 are preferably provided on the rotatable seat enabling the user to steady himself while swinging his legs over the tub wall, with the seat rotating.

From the foregoing taken in connection with the accompanying drawings, it will be seen that

novel and advantageous provision has been made for carrying out the objects of the invention, and while preferred details have been disclosed, variations may of course be made within the scope of the invention as claimed.

I claim:—

1. A bathtub attachment comprising two spaced arched clamps to straddle a bathtub side wall, each of said clamps comprising a crown portion to extend over the tub wall, an inner leg rigidly joined to one end of said crown portion and elongated vertically to lie at the inner side of said tub wall, and an outer leg rigidly joined to the other end of said crown portion to lie at the outer side of said tub wall; a hand rail extending between the inner legs of the two clamps and rigidly joined thereto, and a seat mounted upon the crown portions of the two clamps.

2. A bathtub attachment comprising two spaced arched clamps to straddle a bathtub side wall, each of said clamps comprising a crown portion to extend over the tub wall, an inner vertically elongated leg integrally joined to one end of said crown portion to lie at the inner side of said tub wall, and an outer leg integrally joined to the other end of said crown portion to lie at the outer side of said tub wall; a one-piece grab rail extending between the inner legs of said clamps and having its ends integrally joined thereto, and a seat mounted upon the crown portions of the two clamps.

3. In a bathtub attachment, a clamp to engage the upper portion of a tub side wall, said clamp having a leg for disposition at one side of said wall, a clamp member slidably engaging said leg, said clamp member having a vertical plate at the inner side of said leg and parallel vertical flanges straddling said leg and secured to said plate, said flanges having slots which diverge upwardly with respect to said plate, and projecting means on said leg received in said slots for coaction with said slots to wedge said clamp member to clamping position when said clamp member is slid downwardly on said leg.

4. In a bathtub attachment, a clamp to engage the upper portion of a tub side wall, said clamp having a leg for disposition at one side of said wall, a clamp member slidably engaging said leg, said clamp member having a vertical plate at the inner side of said leg and parallel vertical flanges straddling said leg and secured to said plate, said flanges having slots which diverge upwardly with respect to said plate, and a clamping bolt passing through said leg and through said slots, said bolt and slots being cooperable when said bolt is loosened, to wedge said clamp member to clamping position when said clamp member is slid downwardly.

5. A structure as specified in claim 3, together with a bottom flange connecting the lower ends of said vertical flanges and underlying said leg, and a screw threaded upwardly through said bottom flange and abutting the lower end of said leg for sliding said clamp member downwardly and holding it.

GEORGE B. BENTZ.
